UNITED STATES PATENT OFFICE.

EVERETT J. HALL, OF PASSAIC, NEW JERSEY, ASSIGNOR TO METALS DISINTEGRATING COMPANY, INC., OF NEW YORK, N. Y., A CORPORATION OF NEW YORK.

PROCESS FOR DISINTEGRATING METAL.

Application filed December 20, 1917, Serial No. 208,165. Renewed October 30, 1932. Serial No. 568,011.

This invention relates to the disintegration or reduction of metals to finely divided condition, and the principal objects of the invention are to secure rapid and thorough disintegration and uniform product.

In the attainment of these objects I make use of the atomizing principle, employing a jet or blast of steam or other suitable fluid for breaking up the metal, which is in a molten state, and utilize this flow of disintegrating fluid also to produce an automatic feed of the stream of metal. Thorough disintegration is effected by directing the jet of disintegrating fluid on converging lines upon the stream of molten metal, and the additional suction desirable for more effectively feeding the metal is obtained by giving the jet a whirling or rotary motion, which, further, aids in the disintegration.

In the practical application of the invention, the molten metal issues from a nozzle and this nozzle is kept free of any accumulation or clogging by causing the disintegrating blast to strike the nozzle at a point in back of the nozzle orifice. As the rate of feed and consequent output is largely dependent upon the suction exerted by the disintegrating fluid, or the height of lift of the molten metal, I am able, by regulating these factors, to control the production, both as to quantity and as to fineness of disintegration.

In the accompanying drawing I have illustrated an embodiment of means for carrying out the invention, wherein Figure 1 is a front view of the nozzle and jet producing apparatus, the cover plate being broken away at one side; Figure 2 is a vertical sectional view of the same, showing the connection with the tank holding the molten metal; Figure 3 is a sectional view taken substantially on the plane of line 3-3 of Figure 2; Figure 4 is an illustration of the jet rotating ring, showing it in front and edge views.

The metal to be reduced, such as zinc, aluminum, etc., is maintained in molten condition, within a suitable tank or holder 5, into which dips the pipe 6, leading to a passage 7 in the disintegrating head 8. Set in the forward side of the head and communicating at its rear with supply passage 7, is the nozzle 9. This nozzle may have its outer surface tapered towards the end, as indicated at 10, the angle of this taper being determined by the suction required. Thus, the more acute the angle, the greater the suc-

tion; and the more obtuse the angle, the less the suction. This variable factor of the outside taper of the nozzle makes possible a control of the suction independent of the control resulting from the regulation of the amount of disintegrating fluid or pressure, or that resulting from regulation of the molten metal level, or height of lift. It is often undesirable to lower the level of the metal, because to do so would result in loss of necessary heat to the nozzle.

The heat of the molten metal in the tank, located as it is immediately below the nozzle (in fact the nozzle, by its pipe extension, actually dips into the metal), is sufficient to keep the latter at the required temperature for most effective disintegration, and the relatively short passage provided for the metal from the tank to the nozzle prevents undue cooling of the metal during its travel.

The steam or other feeding and disintegrating fluid is supplied by a pipe 11, communicating with an annular chamber 12, surrounding the nozzle, said pipe entering the chamber tangentially as seen in Figure 3 so as to impart an initial rotation to the fluid. At the front of this expansion chamber 12, is a vane ring 13 having inclined vanes or blades 14, on the rim thereof. This ring, it will be seen, allows the fluid to escape as a hollow rapidly whirling jet and the jet is then condensed or brought down upon the metal-supplying nozzle by a cover plate 15 secured to the face of the head and preferably having a conical depression 16 on its inner face to direct the hollow column of fluid on converging lines into engagement with the nozzle at a point just in rear of the nozzle orifice, the condensed jet finally escaping through the annular jet orifice 17, surrounding the point of the nozzle, the end of the nozzle, as shown, extending appreciably beyond the outer surface of the cap or plate 15.

The flow of disintegrating gas, striking the stream of molten metal simultaneously from all sides, as it does, and on converging lines, instantly breaks it up into the finest particles, reducing it to a powder as fast as it appears at the mouth of the nozzle. This powder is collected as fast as it forms by a suction collecting device or other suitable collecting means. The concentrated convergent flow on the tapered point of the nozzle keeps the nozzle free and clear of any

accumulation. The nozzle orifice is made of a size sufficient to pass a stream such as will be thoroughly disintegrated by the blast or jet in use, but sufficiently large to avoid clogging or choking up within the nozzle. The convergent flow, which is so effective for disintegration purposes, is somewhat less effective for suction producing purposes than would be a plain annular jet, but this loss in feeding efficiency is compensated for by the whirling movement imparted to the jet, the whirling vortex thus produced serving to feed the metal as fast as it is blown off the end of the nozzle.

15 As the rate of feed is dependent upon the degree of suction, I am able, by controlling the flow of disintegrating gas, or the level of the molten metal in the supply tank 5, to regulate the rate of feed and hence the rate

20 and fineness of production. That is, the suction and height of lift determine the amount of metal flowing, providing the metal passage of the nozzle is not less than a certain minimum, where friction must be

25 considered. As the suction is dependent upon the amount of gas flowing, or pressure, a drop in gas pressure means a correspondingly less amount of metal, thereby giving less capacity, but without impairment of

30 quality, since the gas energy, though reduced, will still be ample for the disintegration of the reduced amount of metal. Thus I am enabled to use a nozzle with metal passage large enough to practically eliminate clog-

35 ging; and the control of metal flow depends upon the height of the metal column (height of lift), and on the amount of disintegrating fluid flowing, or pressure. Less pressure of gas, or a lower level of molten metal in the

40 tank means less metal at the nozzle; so that if the gas pressure or the molten metal level fall, no more metal is lifted than may be effectively disintegrated; and assuming a constant gas pressure, the fineness of disinte-

45 gration may be controlled by varying the height of metal in the tank. And, as hereinbefore pointed out, by regulating the angle at which the disintegrating fluid strikes the issuing metal I may vary the suction without

50 changing the gas pressure or height of lift.

The whirling motion of the jet, which may be regulated in an obvious manner, is of further benefit in assisting in the suction or feeding, as well as in the disintegrating action. It increases the degree of vacuum at the tip of the nozzle, thus promoting the feed of metal; and by reason of the centrifugal force generated, back pressure is prevented and disintegration much increased, so that I

55 am able to produce dust of extraordinary fineness and uniformity, and with a simple apparatus that requires but little attention in its operation, because of its automatic mutually compensating controls.

60 65 I have used the term "disintegrating gas"

herein as meaning any form of fluid suitable for the purpose, and it will be understood that other expressions employed herein have likewise been used in a descriptive rather than in a limiting sense.

I claim:

1. The process of disintegrating metal or the like material which comprises striking a stream of molten metal or like material simultaneously and equally on all sides thereof and on convergent angles with a rotating annular flow of disintegrating gas.

2. The process of disintegrating metal or the like material which comprises striking a stream of molten metal or like material on all sides thereof and on convergent angles with a rotating annular flow of disintegrating gas, and varying the angles in accordance with the suction desired.

3. The method which consists in providing a supply of molten metal or the like material, locating a disintegrating nozzle above the level of the material and dipping thereinto, causing fluid under pressure to pass in an annular rotating stream around the nozzle on convergent angles in a direction away from the level of material thereby to exert a suction within the nozzle and upon the supply of material, whereby material is lifted from the supply and discharged through the nozzle, and causing the fluid as it leaves the nozzle to disintegrate the issuing material.

4. The method which consists in providing a supply of molten metal or like material, locating a disintegrating nozzle above the level of the material and dipping thereinto, causing fluid under pressure to pass in an annular rotating stream around the nozzle on convergent angles in a direction away from the level of material thereby to exert a suction within the nozzle and upon the supply of material, whereby the material is lifted from the supply and discharged through the nozzle, causing the fluid as it leaves the nozzle to disintegrate the issuing material, and varying the normal level of the metal supply to regulate the fineness of disintegration.

5. The method of producing metal powder which consists in lifting molten metal or like material from a supply thereof by means of fluid under pressure, disintegrating the material so lifted by means of the fluid so lifting it, and varying the normal level of the material supply independently of variations of the level caused by the action of the pressure fluid to vary the fineness of the resulting powder.

6. The method of producing metal powder which consists in lifting molten metal or like material by means of fluid under pressure, disintegrating the material so lifted by means of the fluid so lifting it, and controlling the level of the material supply independently of variations of the level caused

by the action of the pressure fluid, and the pressure of the fluid to vary the fineness of the resulting powder.

7. The process of disintegrating metal or the like material which comprises striking a cylindrical stream of molten metal or like material simultaneously and equally on all

sides thereof and on convergent angles, with a rotating annular flow of disintegrating fluid, and correlatively regulating the said 10 angles and the pressure of the disintegrating fluid, for the purpose set forth.

In testimony whereof I affix my signature.

EVERETT J. HALL.
